DESIGN FOR A CAKE SERVER OR SIMILAR ARTICLE

Harry Rietveld, Milwaukee, Wis.

Substituted for abandoned application Serial No. D-65,421, October 22, 1936. This application September 10, 1937, Serial No. 71,561

Term of patent 7 years

To all whom it may concern:

Be it known that I, Harry Rietveld, a citizen of the United States and resident of Milwaukee, in the county of Milwaukee and State of Wisconsin, have invented a new, original, and ornamental Design for a Cake Server or Similar Article, of which the following is a specification, reference being had to the accompanying drawing, forming part thereof.

This application is a substitute for the application filed by applicant October 22, 1936, bearing Serial No. D-65,421, now abandoned.

I claim:

The ornamental design for a cake server or similar article as shown.

HARRY RIETVELD.
